Fig. 3.

Fig. 4.

Fig. 5.

FIG. 1 is a top perspective view of a funnel top for sprayer unit showing my new design;

FIG. 2 is a top plan view thereof;

FIG. 3 is a side elevational view thereof, the opposite side being a mirror image of the side shown;

FIG. 4 is a side elevational view taken 90 degrees from FIG. 3, the opposite side being a mirror image of the side shown;

FIG. 5 is a bottom plan view thereof; and

FIG. 6 is a cross sectional view taken on line 6-6 of FIG. 2.

The broken line representation of a sprayer unit in FIG. 1 is for purposes of illustration only.

I claim:

The ornamental design for a funnel top for sprayer unit, as shown and described.
